UNITED STATES PATENT OFFICE.

CHARLES EDOUARD JULES O'KEENAN, OF ST. CLOUD, FRANCE.

ELECTRIC METER.

957,792.

Specification of Letters Patent. Patented May 10, 1910.

Application filed June 28, 1909. Serial No. 504,845.

To all whom it may concern:

Be it known that I, CHARLES EDOUARD JULES O'KEENAN, a citizen of the French Republic, residing at 5 Rue des Grands 5 Champs, St. Cloud, in France, have invented certain new and useful Improvements in Electric Meters, of which the following is a specification.

The present invention enables one, by 10 means of a new device to obtain a fall of potential (or an electric current) proportional to the watts absorbed in a continuous current circuit. This fall of potential or this current can then act on the armature of 15 a meter (such as that patented by me in the United States on January 9, 1900, No. 641,140 known under the name of the O'K. meter) or upon the armature of any other suitable meter whether provided with a brake or not, 20 thus forming a watt-hour meter; or this fall of potential (or current) could act on a millivoltmeter ammeter of the Weston, Chauvin and Arnoux, Deprez-d'Arsonval, Meylan d'Arsonval or other type, so as to 25 form a wattmeter which can be read directly.

In the accompanying drawings—Figure 1 represents diagrammatically one form of my improved meter. Fig. 2 is a similar 30 diagrammatic view of a slightly modified form. Fig. 3 is a side view showing the construction of the shunt portion of the meter. Fig. 4 is a similar view showing part of the shunt incased in vacuum tubes. Fig. 35 5 is a diagrammatic view showing the complete meter. Figs. 6 and 7 are diagrammatic views showing different arrangements of shunt and motor, and Figs. 8 and 9 are diagrammatic views showing modifications.

40 Suppose A B to be the shunt of an O'K. meter (Fig. 1) traversed by a continuous current in the direction of the double arrows, it is known that under these conditions there will be a fall in potential between 45 points A and B proportional to the intensity of the current passing through it and that since the ends of the circuits of the armature of the motor are divided at A and B, the said motor will revolve at a speed proportional to the number of volts-hours produced at the terminals of the shunt and consequently proportional to the number of amperes-hours absorbed by the consumer.

50 In the new arrangement between the 55 points A and B of the shunt is connected a

copper or nickel wire A C B; this wire derives a more or less important part of the current primarily passing through the shunt, in accordance with the well known law of derived currents.

60

Around the portion of the wire designated C B to which the applicant gives the name of "sub-shunt" is coiled a long winding b of fine German silver wire or of some conductor having a negative temperature coefficient. The ends of this winding are connected to the points A' and A² between which there exists a difference of potential U which, multiplied by the current I, represents the number of watts absorbed by the 70 consumer; this fine wire-coil is warmed by the current due to the potential difference U and also warms the sub-shunt C B which it incloses. Now the warming of the coil and consequently of the wire C B is proportional 75 to the square of the current passing through the coil, that is to say to the square of the difference of potential U. But according to a development of the well known binomial theorem, it is known that between certain 80 limits, a sufficiently approximate proportionality exists between the increase in a function Θ, which is proportional to the square U² of a variable, and the increase in this variable U, provided that this increase 85 is sufficiently small. The result is that the variation in degrees centigrade in the temperature of the coil and of the wire C B is proportional to the variations in U, within certain limits, provided of course that sufficient 90 time is allowed for the temperature equilibrium to establish itself on each occasion. Now when the temperature Θ of the wire or subshunt rises, its coefficient of temperature α causes the resistance therein to increase, so that the current passing through the subshunt diminishes, but as the resistance of the wire A C remains on the contrary practically constant, the result is that finally, the fall in potential at the terminals 100 of the subshunt C B is increased, for the current diminishes less, in proportion, in the subshunt than the resistance of the said subshunt increases and the product, $i^2 r^2 = u'$, of the potential at its terminals, Fig. 6, is 105 increased when U is increased.

From the foregoing it follows that a point D can be found in the shunt A B which point in certain cases can coincide with the point B of the subshunt as in Fig. 7, such 110

that the difference of the potentials u'' (or current) between points C and D are proportional, when temperature equilibrium is established, to the watts absorbed at the same time in the installation, moreover this difference in potential (or current) is not sensibly affected by variations either of the surrounding temperature, or of the heating due to the current derived from the shunt 10 A B which passes through the wires A C, C B and C D, provided that care is taken in the construction to arrange that the increases in temperature due to the heating produced by these currents, are practically identical. This can be provided for by covering these wires to a greater or less extent determined by experiment, with heat insulating substances such as cotton wool, "glass wool" or other suitable material, or by 20 bringing their windings closer together or by any other suitable means. One could also, in order to avoid the effect of the heating of the wire A C B by current derived from shunt A B, diminish this said current 25 by making the ohmic resistance of this wire A C B sufficiently great.

In a case where the device M is a motor or an electrolytic meter, the same current can be used if desired to compound the said 30 meter as is done at present in the O'K. motor or in the Wright electrolytic meter, by means of introducing a very small constant fall of additional potential. That is obtained in Fig. 2 by means of the portion 35 F C of the wire which is traversed by the fine wire current, the motor or the electrolyte M being connected between F and D instead of between C and D.

Fig. 3 shows a practical form of the present invention.

f' is a small coil of wire of copper or of nickel or other suitable metal covered with silk or other appropriate substance, and represents the wire A C in the diagram, f'' is another small coil of copper or nickel wire covered with silk or other material suitable for the purpose constituting the watt metric subshunt, b is a section through the coil of fine heating wire intended to be traversed by 50 the current due to the potential U.

g represents a kind of sheath of cotton-wool or other suitable material, intended to diminish the loss of heat from the wire b so that the internal temperature of the coil b 55 and of the sub-shunt f'' can be raised sufficiently with a slight expenditure of power in the fine wire. It must be remarked however that this process of sheathing increases the time of shifting between the variation 60 of U and the variation of the temperature corresponding to a new equilibrium. This would not generally be an inconvenience for the meters but when the shifting of these 65 two quantities is to be reduced, the thickness of the heat insulator g may be diminished

and one could even suppress it completely in certain cases. Instead of using cotton-wool or a heat insulator, one could diminish the loss by convection by placing the coils f'' and b , and if desired f' , in one or two 70 vacuum tubes o and o' (Figs. 4 and 5) and at will by using iron as the metal with a great positive coefficient of temperature instead of copper or nickel, as is done in the additional resistances in the Nernst lamps, 75 or some other suitable metal, such as steel. These metals could also if desired be exposed directly to the air, being protected from oxidation by suitable processes.

If instead of devices designed for acting 80 with a variable current in a network having an almost constant potential as in the cases mentioned above, it is desired to use the same system to measure watts in the case of a current substantially constant with a 85 variable potential, as in the Bernstein or Thury systems, where the translating devices are all included in the same circuit, one could use one of the arrangements shown diagrammatically in Figs. 8 and 9, which 90 are very similar to those already shown for variable current and almost constant potential, and can be understood at a glance. The principal differences consist solely in that the heating coil b instead of being traversed 95 by the potential current is traversed by the main current (or a derivation of this current is preferred) while the sub-shunt B C is traversed by the potential current or a derivation 100 of this current. In this manner voltmeters may be transformed into watt meters and volt hour meters into watt hour meters.

Instead of transforming an ampere hour meter or volt hour meter into a watt hour meter one could transform a galvanometer 105 of the Deprez d'Arsonval type (with or without mirror) or a millivolt meter ammeter of the Weston or other type into direct reading shunt watt meters. Supposing M to be a Weston millivoltmeter, connections 110 with the sub-shunt may be made with the wires of the vacuum tube as shown for example in Fig. 5, and the apparatus will indicate directly on a proper scale the watts absorbed by the installation $l l$ for example. 115

If preferred the apparatus could operate with the sub-shunt exposed to the air and surrounded or not, by cotton-wool or some other suitable heat insulating substance.

The same device can be used in the same way to transform Meylan d'Arsonval, Chauvin-Arnoux or other ammeters into wattmeters as will be obvious without further explanation. In transforming these latter apparatus there is no necessity for compoundage such as described above, for the purpose of balancing the friction in the O'K. or other meters or the counter electromotive forces of electrolysis in the case of Wright or other electrolytic-meters.

In the case of a calorific shunt ammeter, the subshunt enables the watts absorbed in alternating current circuits to be measured.

I claim:—

- 5 1. In a device for obtaining a fall of potential proportional to the watts absorbed in a continuous current circuit, the combination of a shunt, a sub-shunt, and a winding for heating the sub-shunt, the ends of said winding being connected to the main conductors of the installation, substantially as described.
- 10 2. In a device for obtaining a fall of potential proportional to the watts absorbed in

a continuous current circuit, the combination 15 of a shunt, a sub-shunt, a winding for heating the sub-shunt, the ends of said winding being connected to the main conductors of the installation, and a motor meter connected between the sub-shunt and the shunt, 20 substantially as described.

In witness whereof I have hereunto set my hand this 16th day of June, 1909, in presence of two subscribing witnesses.

CHARLES EDOUARD JULES O'KEEANAN.
